LEWIS E. CURTIS, OF MILWAUKEE, WISCONSIN, ASSIGNOR, BY MESNE ASSIGNMENTS, TO A. C. PAUL, OF MINNEAPOLIS, MINNESOTA, AND GEORGE A. CHRITTON, OF RIVER FOREST, ILLINOIS, TRUSTEES.

APPARATUS FOR EXPANDING METAL LATH.

Application filed July 26, 1924, Serial No. 728,420. Renewed January 24, 1927.

The present invention relates to improvements in machines for expanding metal lath, and particularly the type of metal lath known as ribbed lath. It will be fully understood from the following description, illustrated by the accompanying drawings, in which:

Figures 1 and 1^a together present a side elevation of a machine constructed in accordance with this invention;

Figs. 2 and 2^a present a plan view thereof;

Fig. 3 is a vertical sectional view through the feeding and rib forming rolls on the line 3 of Fig. 2;

Fig. 4 is a vertical sectional view through intermediate guide rolls on the line 4 of Fig. 2;

Fig. 5 is a vertical sectional view through expanding guides on the line 5 of Fig. 2;

Fig. 6 is a longitudinal vertical section on the broken line 6 of Fig. 5, showing an intermediate expanding guide in side elevation;

Fig. 7 is a broken detail sectional view through the guide rolls on the line 7 of Fig. 6;

Fig. 8 is a detail sectional view on the line 8 of Fig. 6;

Fig. 9 is a vertical sectional view on the line 9 of Fig. 5, showing an intermediate expanding guide in side elevation;

Fig. 10 is a plan view of the lower guides and rolls shown in Fig. 9;

Fig. 11 is a vertical sectional view through the central guide portion shown in Fig. 9;

Fig. 12 is a vertical sectional view on the line 12 of Fig. 5, showing the marginal expanding guides in side elevation;

Fig. 13 is a plan view of the lower guides and rolls as shown in Fig. 12;

Fig. 14 is a detail sectional view on the line 14 of Fig. 12;

Fig. 15 is a detail sectional view on the line 15 of Fig. 12; and

Fig. 16 is a vertical sectional view through the flattening rolls on the line 16 of Figs. 1^a and 2^a.

Referring more particularly to the embodiment of the invention shown in the drawings, the numeral 20 indicates a supporting frame or table upon which the expanding machine is mounted. To one end thereof is secured the guide or feed table 21, by which a previously slotted blank is fed to the expanding machine. Adjacent to the feed

table are provided the feeding and rib forming rolls, of which, in the form illustrated, there are upper sets of rolls 22 mounted on shafts 23 and lower sets of rolls 24 mounted on shafts 25, the upper and lower sets of rolls mating with one another. The lower shafts 25 are journaled in the end bearing blocks 26 and intermediate bearings 27. The upper shafts 23 are journaled in the end bearing blocks 28 slidable in the supporting frame 28^a and in the intermediate bearing 29 suspended adjustably by means of a screw 30 from the supporting yoke 31, mounted on the frame 28^a. The upper and lower feed roll shafts 23 and 25 are driven together by means of the intermeshing gears 32, and suitable gearing 35 is provided for driving the two sets of rolls simultaneously. One of the lower shafts 25 is extended outwardly to one side, the extended portion 25^a being journaled in a bearing block 36 and provided at 75 its end with a sprocket wheel 37, by which the feed rolls are driven as hereinafter set forth.

The respective feed rolls 22 and 24 are provided with mating grooves and tongues 80 to form the desired ribs in the blank being fed through the machine.

After leaving the grooving and feed rolls 22 and 24, the blank passes alternately through stationary expanders, indicated as a group in Figs. 1, 1^a, 2 and 2^a by the numeral 38, and feed rolls 79.

As shown in Figs. 5 to 15 inclusive, the stationary expanders are of several types. For convenience these may be designated as 90 the central guides 40, the intermediate guides 41 and the marginal guides 42. In the form shown, three center guides are provided, one of them being in a position corresponding to the center of the sheet, and 95 one being provided on each side thereof, the position of the parts in the central of these guides, designated 40^a, being reversed to that of the parts of those on each side of it. As these guides are otherwise substantially 100 similar in form, only the central one of the group will be described in detail.

As shown in Figs. 5, 6 and 8, this guide member consists of a lower bar 43, mounted at its ends on the supports 44 and having 105 beveled ends projecting into the space between the adjacent feed rolls at each end thereof. On its upper surface longitudinal

portions are cut away to form shoulders 45, and in these are secured the bars 46 (suitably formed of hardened metal) which extend upwardly above the upper surface of the guide bars 43, thereby forming a substantially grooved guide. The opposed guide member 47, is substantially flat on its surface opposed to guide member 43. It is supported near its ends by the transverse supporting bars 48 suitably spaced from and secured to the supporting members 44, for example, as shown in Fig. 5. Double ended screws 49 are screwed into the supporting member 44 at each end, being fixed in position by lock nuts 51, and the supporting bars 48 are secured to the upper ends of these screws by means of the nuts 52. As shown in that figure, the expander guides on each side of the center guide are similarly constructed, the groove being formed in the upper guide member and the opposing face of the lower guide member being flat. Figure 8 shows the conformation assumed by a rib of an expanding blank as it passes through these guides.

Certain intermediate guides are provided as shown in Figs. 5, 9, 10 and 11. Each of these intermediate guides consist of a lower guide member 53, secured to the supports 44 near its ends, and like the guide member 43, having its ends tapered to project between the adjacent feed rolls. The corresponding upper guide 56 is secured to the transverse supporting bars 48. The expander members 53 and 56 are slotted out at intervals as shown at 57 and 58 respectively. In the slots thus formed in the lower expander member 53 there are rotatably mounted the grooved rolls 59, and in the slots 58 in the upper expander member 56 are rotatably mounted the narrow rolls or disks 60. The rolls 59 and 60 do not mate with one another, but are alternately engaged by the blank passing therethrough.

As the blank passes through the machine, a rib of the blank passes between the guides 53 and 56, its outer margins and its inner surface being alternately engaged by the rolls 59 and 60 respectively.

The construction of the marginal expanding guides 42 is shown in detail in Figs. 5 and 12 to 15 inclusive. Each of these dies or guides consist of a lower guide member 61, mounted on the supports 44 and the upper, generally L-shaped guide members 62 secured to the supporting bars 48. The lower guide member 61 is slotted out at intervals, as at 63, and in the slots are rotatably mounted the small rolls 64 provided near their margins with a raised portion or tongue 65, which engages within the marginal rib of the blank undergoing expansion, as shown in Figs. 14 and 15. Opposite the rollers 64 there are rotatably secured to the upper guide 62 the rollers 66,

likewise provided with a projecting tongue 67 which engages the blank just within the rib. Between the rollers 66 the angularly disposed disks 68 are rotatably mounted upon a beveled surface 69 of the upper guide member 62. The disks 68 have their edges beveled and engage the expanding blank on the inner portion of the marginal rib, the disks 68 alternating with the opposed rolls 64 and 66. These opposed rolls, together with the disks 68 retain and support the marginal rib of the sheet during expansion of the blank.

Alternating with the sets of expanding ribs as hereinbefore described are the guiding and feeding members, illustrated in detail in Fig. 4, and in conjunction with the expanding guides in Figs. 6, 9 and 12. Each of these feeding and guiding members comprises upper and lower feeding shafts 70 and 71 respectively. The lower shaft 71 in each case is mounted in lower bearing blocks 72 supported in a frame 75 mounted on the table 20. An intermediate bearing 73 may likewise be provided. The upper feed shaft 70 in each case is mounted in end bearing blocks 74 slidable in the frame 75 and held in position by springs 75^a, the tension of which is adjustable from the yoke 75^b by the screws 76. An intermediate bearing 77 may also be provided, suspended from the yoke 75^b by means of a screw 78.

On the shafts 70 and 71 are provided at suitable intervals the opposed tongued and grooved rolls 79, the spacing and position of the groove in each case being determined by the formation of the ribs on the blank passing through the machine and by the extent to which it has been expanded. The shafts 70 and 71 are provided with mating gears 80, so that they may be driven in unison, and a sprocket wheel 81 is secured to a projecting end of each shaft 71.

After passing through the expanding dies and feed rolls, the expanded blank passes between the flattening rolls 82 and 83 by which the expanded metal is flattened out and distortions are removed. The flattening rolls are mounted in a lower supporting frame 85 secured to the table 20 and the upper supporting frame 86, mounted on rods 87 rising from the lower frame 85. The lower limit of movement of the upper supporting frame 86 is determined by the nuts 88, against which the upper supporting frame 86 is forced by the springs 89.

In the embodiment shown, three flattening rolls are mounted in each of the supporting frames 85 and 86, the upper flattening rolls being designated by the numeral 82 and the lower by the numeral 83. The upper and lower rolls 82 and 83 are respectively alternately disposed. At one end, the rolls 82 and 83 project beyond the frame and the gears 92 are secured thereto. These

gears mesh with one another and with a gear 93 mounted on a transverse shaft 94 journaled in the lower supporting frame 85. On the opposite end of this shaft 94 is mounted the sprocket wheel 95, which is driven by a chain 96 from a sprocket wheel 97 mounted on a projection from the driven shaft 71 of the adjacent set of feed rolls.

A feed shaft 71 of one of the sets of feed rolls is projected beyond the sprocket wheel 81 and to it is secured the gear 100. This gear 100 meshes with a gear 101 mounted on a short shaft 102 journaled on one end in the wall of the table 20 and at its other end in the supporting frame or yoke 103. On this shaft 102 is also mounted a sprocket wheel 104 which is driven by a chain 105 from a sprocket wheel 106 on the shaft of the motor 107. The motor, through the sprocket wheels 106 and 104 and the chain 105 drives the shaft 102, which in turn through gears 101 and 100, drives the shafts 71 to which the latter gear is secured. A suitable sprocket chain 96 connects the various sprocket wheels 81 of the feed rolls as well as the sprocket wheels 37 of the initial feeding and grooving rolls, this chain being guided in its path by the idler sprocket wheels 107 mounted in the guide roll supporting frames 75 and by the idler sprockets 108 mounted on the side of the table 20. The end feed roll, through the sprockets 97 and 95 and the chain 96 drives the flattening rolls 80.

In operation, the previously slitted metal blank is fed through the feed table 20 to the grooving and feeding rolls 22 and 24, by which the proper grooves or ribs are formed in the metal between the longitudinal series 40 of slits in the blank. From the grooving and feeding rolls the blank passes to the first set of expanding dies, which engage the ribs, and, by their divergence partially expand the slitted portions of the blanks between the ribs. The blank then passes between the first set of grooved feeding rolls 79 and to the next group of stationary expander guides 38, by which the metal is further expanded. These operations are repeated until the expansion of the metal is complete, the metal then passing between the grooved flattening rolls 82 and 83.

Although the present invention has been described in connection with the specific details of a device embodying it, it is not intended that these details shall be regarded as limitations upon the scope of the invention, except in so far as included in the accompanying claims.

I claim:

1. In apparatus for expanding slitted metal blanks, means for forming ribs in said blanks and advancing them through the machine, and diverging expander members for receiving the blanks and engaging the

ribs formed therein, said expander members comprising means for alternately engaging the interior of the ribs and the exterior margins thereof.

2. In apparatus for expanding slitted metal blanks, means for forming ribs in said blanks and advancing them through the machine, a succession of sets of diverging expander members for receiving the blanks and engaging the ribs formed therein, said expander members comprising means for alternately engaging the interior of the ribs and the exterior margins thereof, and feed rolls between the successive sets of expander members having means for engaging the ribs of the blanks passing therethrough.

3. In apparatus for expanding previously slitted metal blanks provided with longitudinal ribs, diverging stationary expander members having means for alternately engaging the interior of the ribs and the exterior margins thereof.

4. In apparatus for expanding previously slitted metal blanks provided with longitudinal ribs, a stationary expander die comprising opposed die members, one having spaced rolls for engaging the interior of a rib of the blank and the other having spaced rolls for engaging an exterior margin of a rib, the rolls of one of the die members being positioned between the rolls of the other die member.

5. In apparatus for expanding previously slitted metal blanks provided with longitudinal ribs, a stationary expander die comprising opposed die members, one having spaced rolls for entering the interior of a rib of the blank and the other having spaced grooved rolls engaging the exterior margins of the rib, the rolls of one of the die members being positioned between those of the other.

6. In apparatus for expanding previously slitted metal blanks provided with a marginal rib, a stationary expander die comprising a die member having means for engaging the interior of the marginal rib and an opposed die member having angularly disposed spaced members engaging the internal margin and side of the marginal rib.

7. In apparatus for expanding previously slitted metal blanks provided with a marginal rib, a stationary expander die comprising a die member having spaced rolls provided with tongues adapted to fit within the marginal rib and an opposed die member having spaced angularly inclined rollers engaging the inner side of the marginal rib.

8. In apparatus for expanding previously slitted metal blanks provided with a marginal rib, a stationary expander die comprising a die member having spaced rolls provided with tongues adapted to fit within the marginal rib and an opposed die member

having spaced angularly inclined rollers engaging the inner side of the marginal rib, said inclined rollers being disposed between the rollers of the other die member.

5 9. In apparatus for expanding previously slotted metal blanks provided with a marginal rib, a stationary expander die com-

prising opposed die members having spaced mating rolls fitting the interior and exterior of the marginal rib, one of said dies being ¹⁰ provided alternately of said rolls with angularly inclined rollers engaging the inner side of the marginal rib.

LEWIS E. CURTIS.
